UNITED STATES PATENT OFFICE

JOHN J. PUNKE, OF DETROIT, MICHIGAN, ASSIGNOR TO HUPP MOTOR CAR CORPORATION, OF DETROIT, MICHIGAN, A CORPORATION OF VIRGINIA

DESIGN FOR A HUB CAP

Application filed December 22, 1930. Serial No. 38,061. Term of patent 7 years.

To all whom it may concern:

Be it known that I, JOHN J. PUNKE, a citizen of the United States of America, residing at Detroit, in the county of Wayne, and State of Michigan, have invented a certain new, original, and ornamental Design for Hub Cap, of which the following is a specification, reference being had therein to the accompanying drawings, forming a part thereof, wherein—

The dominant feature of my new design is the portions arranged in different planes in the surface of the cap forming a design thereon, a portion of which constitutes a letter of the alphabet.

I claim:

The ornamental design for a hub cap substantially as shown and described.

JOHN J. PUNKE.
